UNITED STATES PATENT OFFICE.

JOHN F. O'CONNOR, OF CHICAGO, ILLINOIS, ASSIGNOR TO WILLIAM H. MINER, OF CHICAGO, ILLINOIS.

FRICITION-BUFFER FOR RAILWAY PASSENGER-CARS.

992,440.

specification of Letters Patent. Patented May 16, 1911.

Application filed October 27, 1910. Serial No. 589,448.

To all whom it may concern:

Be it known that I, JOHN F. O'CONNOR, a citizen of the United States, residing in Chicago, in the county of Cook and State of Illinois, have invented a new and useful Improvement in Friction-Buffers for Railway Passenger-Cars, of which the following is a specification.

My invention relates to improvements in friction buffers for railway cars, and more particularly for use upon railway passenger cars.

The object of my invention is to provide a friction buffer of a strong, simple, efficient and durable construction, and having a plurality of simultaneously acting main or primary buffer springs in connection with a friction cushioning mechanism.

My invention consists in the novel construction of parts and devices and in the novel combinations of parts and devices herein shown and described and more particularly specified in the claims.

In the accompanying drawing forming a part of this specification, Figure 1 is a plan view of a friction buffer embodying my invention. Fig. 2 is a side elevation, partly in central, longitudinal section on line 2—2 of Fig. 1. Fig. 3 is a detail, vertical section showing the buffer compressed, one shoe being shown in elevation. Fig. 4 is a detail view of the front spring seat or cage for the group or plurality of main or primary buffer springs. Fig. 5 is a detail elevation of the rear spring seat or cage for the group or plurality of main or primary buffer springs. Fig. 6 is a detail cross section of the friction shell and contained parts on line 6—6 of Fig. 1. Fig. 7 is a detail elevation of the wedge. Fig. 8 is a detail perspective view of one of the friction shoes. Fig. 9 is a detail perspective view of the friction shell. Fig. 10 is a detail perspective view of one of the anti-friction rollers. Fig. 11 is a detail perspective view of the cap which fits in the rear end of the friction shell. Fig. 12 is a detail perspective view of the intermediate thrust member which is interposed between the front spring seat and

the wedge of the friction cushioning mechanism. Fig. 13 is a detail perspective view of the front spring seat or cage and Fig. 14 is a detail perspective view of the rear spring seat or cage.

In the drawing, 1 represents a portion of the front end frame of a railway passenger car, 2 the buffer frame or cradle, 3 the steel floor plate of the vestibule of the car, preferably secured to and supported by the buffer frame or cradle 2; 4 the buffer plate, 5 the buffer bar, all these parts being of any ordinary or suitable construction adapted to give support and mounting to the other parts.

The main or primary buffer springs 6 are preferably four in number in twin or side by side arrangement, for simultaneous action. The group or plurality of main or primary buffer springs bear at their front ends against a spring seat or cage 7, which is interposed between the front ends of the springs and the buffer bar. At its front face this front spring seat or cage 7 has a rectangular socket 8 to receive the rear end of the buffer bar 5, and it is preferably of generally rectangular shape to fit upon the floor or bottom web 9 of the buffer frame or cradle 2, and it is provided at its rear end with a group of four segmental seats or sockets 10, one for each of the springs 6, to receive and partially inclose and thus hold and support the front ends of the springs in proper position in relation to each other.

At their rear ends the group of twin or side by side arranged springs 6 bear against a spring seat or cage 11 which is furnished at its front end with four segmental sockets or seats 12 corresponding to the seats or sockets 10 of the front spring seat or cage 7. The spring seats or cages 7, 11, by their abutment directly together at their adjacent ends 13, 14, also serve as stops to limit the extent of compression of the main buffer springs. At its rear end, the rear spring seat or cage 11 is provided with an extension 15, preferably of cylindrical shape, and furnished with segmental projections 16 to engage the front end of the friction shell 17, which abuts at its front end against said rear

- spring cage 11 and at its rear end against the upright or transverse web 18 of the buffer frame or cradle 2. The rear spring cage thus serves as a thrust member between 5 the friction shell and the front spring cage or follower 7; and the cages 7 and 11 also abut together after full compression of the main buffer springs 6 and thereby protect the springs from injury.
- 10 The secondary or friction mechanism springs 19, 20, fit inside the friction shell 17 and react at their front ends against the friction shoes 21, and at their rear ends against the friction shell 17, which is furnished with a flange 22 for the larger spring to bear against, and with a removable cap 23 for the inner or smaller spring to bear against. The cap 23 has an external flange 24 fitting in a recess 25 of the end flange 22 15 of the friction shell. The cap 23 is cup shaped and fits within the rear end of the outer or larger spring 19, and thus serves as a seat or guide for said spring.
- 15 The friction shell 17 is cylindrical in form and has an internal cylindric friction face 26 in sliding frictional engagement with the external cylindric friction faces 27 of the segmental friction shoes 21, the shoes being preferably three in number, and each having a 20 wedge face 28 and stop shoulder 29 for the anti-friction roller 30, which is interposed between each of the friction shoes 21 and the wedge 31, which has a corresponding number of wedge faces 32 and stop shoulders 33 25 for the anti-friction rollers.

To transmit the thrust of the main buffer bar and front spring cage or follower 7 to the wedge 31, and thus cause the friction cushioning mechanism to come into action, 40 a secondary thrust member 34, having segmental curved faces 35 to receive the four primary buffer springs 6, and fitting centrally between the same, and is interposed between the wedge 31 and front spring cage 45 or follower 7, so that after the group of main buffer springs 6 have been partially compressed, the further movement of the buffer bar will actuate the wedge 31, friction shoes 21 and secondary buffer springs 19, 20 which 50 are interposed between the friction shoes and the rear end of the friction shell. The secondary thrust member 34 is also provided at its rear end with an external flange 36 which engages the internal flange or shoulder 37 of 55 the rear spring cage 11.

A connecting bolt 38 extending between the front spring cage 7 and the secondary thrust member 34 holds the spring cages 7, 11 and group of primary buffer springs 6 60 and secondary thrust member 34, all in assembled position. And a connecting bolt 39, extending between the wedge 31 and rear end cap 23 of the friction shell holds the

friction shell, friction shoes, springs 19, 20, and wedge all assembled in position together. 65

The friction shell 17 is provided on its upper and lower faces with straight flat faced projections 40, which hold the friction shell from turning and which fit between the adjacent ends 41, 41 of the segmental flanges 70 16 of the rear spring cage or intermediate thrust member 11.

By employing a group or plurality of primary buffer springs 6 in connection with the friction cushioning mechanism 17, 19, 75 20, 21, 31, the necessary extended movement of the buffer bar for passenger car use is provided for, while at the same time the combined spring and friction cushioning mechanism as a whole is relatively short, as the 80 four primary buffer springs together give the required amount of spring resistance or capacity when made of relatively small rods, whereas, in cases where a single main buffer spring is employed, the rod of which the 85 spring is made is necessarily so large in diameter that the spring has to be of great length in order to afford the required movement in compression.

I claim:—

1. In a friction buffer, the combination with a buffer bar, of a plurality of main buffer springs arranged side by side, front and rear spring cages against which said main buffer springs react, a friction shell, 90 friction shoes and wedge within said shell, a spring within said shell reacting at one end against said friction shoes, and a secondary thrust member interposed between said wedge and said front spring cage and operating to transmit the pressure of the buffer bar to the wedge independent of said main buffer springs, substantially as specified.

2. In a friction buffer, the combination with a buffer bar, of a plurality of main buffer springs arranged side by side, front and rear spring cages against which said main buffer springs react, a friction shell, friction shoes and wedge within said shell, a spring within said shell reacting at one end 105 against said friction shoes, and a secondary thrust member interposed between said wedge and said front spring cage and operating to transmit the pressure of the buffer bar to the wedge independent of said main 110 buffer springs, said secondary thrust member fitting centrally between said springs, substantially as specified.

3. In a friction buffer, the combination with a buffer bar, of a plurality of main 120 buffer springs arranged side by side, front and rear spring cages against which said main buffer springs react, a friction shell, friction shoes and wedge within said shell, a spring within said shell reacting at one end 125 against said friction shoes, and a secondary

thrust member interposed between said wedge and said front spring cage and operating to transmit the pressure of the buffer bar to the wedge independent of said main buffer springs, said secondary thrust member fitting centrally between said springs, and having longitudinally extending recesses to receive said springs, substantially as specified.

JOHN F. O'CONNOR.
